LEVER OPERATED TOY CAP GUN
 Mahlon E. Hirsch, Fairview, and Raymond J. Lohr, Erie,
 Pa., assignors to Louis Marx & Company, Inc., New
 York, N.Y., a corporation of New York
 Filed Sept. 21, 1959, Ser. No. 57,417
 10 Claims. (Cl. 42—57)

This invention relates to toy guns, and more particularly to cap firing guns.

The general object of the present invention is to improve toy guns. A real gun makes a percussive noise, with a sharp recoil, accompanied by the smoke and smell of gun powder. Toy cap guns are fairly realistic in many respects, but they have no recoil. The primary object of the present invention is to improve toy guns by providing the same with realistic recoil force. A more specific object is to combine the new recoil mechanism with the regular cocking mechanism so that the latter stresses both the hammer spring of the gun and the recoil mechanism, and the trigger releases both.

To accomplish the foregoing general objects, and other more specific objects which will hereinafter appear, our invention resides in the toy gun elements and their relation one to another, as are hereinafter more particularly described in the following specification. The specification is accompanied by drawings in which:

FIG. 1 is a perspective view showing a toy cap rifle embodying features of our invention;

FIG. 2 shows the rear portion of the gun, with one side of the gun body removed to expose the mechanism therein;

FIG. 3 is a fragmentary approximately horizontal section taken in the plane of the line 3—3 of FIG. 2, and drawn to enlarged scale;

FIG. 3A shows a fragment of a double cap strip used in the present gun;

FIG. 4 is a view similar to FIG. 2, but with the cocking lever turned down;

FIG. 4A is a fragmentary view corresponding to a part of FIG. 4, but with the guide rod and recoil spring removed.

FIG. 5 is a view similar to FIG. 4, but with the cocking lever restored, and with the hammer and recoil springs compressed;

FIG. 6 is a fragmentary view similar to FIG. 5, but showing the relation of the parts as the trigger is pulled;

FIG. 7 shows the opposite side of the rear portion of the gun body, without the recoil mechanism, and with the cap mechanism turned down for reloading with a new load of caps;

FIG. 8 is a transverse section taken approximately in the plane of the line 8—8 of FIG. 4;

FIG. 9 is a transverse section taken approximately in the plane of the line 9—9 of FIG. 4; and

FIG. 10 is a somewhat schematic view explanatory of the cap firing mechanism.

Referring to the drawing, and more particularly to FIG. 1, the invention is here shown embodied in a toy cap-shooting rifle. This comprises a simulated barrel 12 and stock 14, with a cocking lever 16 and trigger 18. The body of the gun may be molded in two halves out of a suitable plastics molding material, the halves being separated on a vertical parting plane passing substantially through the center of the barrel 12 and stock 14. The exterior of the gun may be suitably embellished and ornamented to improve its realism, as by the provision of simulated sights 20 and 22 and a simulated hammer 24. The parts 14 and 26 may be grained to better simulate wood. However, the actual working mechanism is preferably made of metal, most of the parts being die cast, including the cocking lever 16 and the trigger 18.

Referring now to FIGS. 2, 5, and 9 of the drawing, the

2

recoil simulating mechanism comprises a recoil weight 30, a spring 32 for moving the weight 30 abruptly and preferably rearward in a direction longitudinal of the gun, and cocking mechanism actuated by the cocking lever 16 to stress the spring 32, as shown by the change from FIG. 4 to FIG. 5, while the trigger 18 serves to release the recoil weight and spring in order to simulate recoil.

The particular gun shown is a cap firing gun, and it employs caps in strip or roll form, as shown at 34 in FIGS. 10 and 11. The gun accordingly has cap strip feeding and firing mechanism, including an anvil 36 (FIG. 10) which in the present case is a rotatable cylindrical anvil, and a hammer 40, which in the present case moves nearly horizontally. The cap strip feeding mechanism includes a ratchet wheel 42 (FIG. 4) and a pawl 44, the latter being connected at 46 to the hammer 40 (not visible in FIG. 4).

Reverting to FIG. 10, the hammer 40 is actuated by a hammer spring 48, and is held in rearward position by a sear 50, which in the present case is directly connected to, and indeed is formed integrally with the trigger 18. It will be evident that pulling the trigger releases the hammer to strike the cap strip on the anvil 36.

Considering the mechanism in somewhat greater detail, and referring to FIGS. 2, 4, 5, and 6, the recoil simulating mechanism includes a guide rod 52 disposed longitudinally of the stock 14 of the gun. The recoil spring 32 is a compression spring coiled around the guide rod 52. There is a bumper 54 made of rubber or other resilient material at the rear end of the rod 52, this being backed by a washer 56, which in turn is arrested by stops 58 which are pinch excised from the rod 52.

The recoil weight 30 has a part 60 disposed between the spring 32 and the bumper 54. There is also means to guide the weight for movement longitudinally of the rod. In the present case the rear portion 60 is astride the rod 52, while the forward portion 62 is astride the spring 32. These parts are integral with a main weight body disposed at the side of the rod 52 and spring 32, as is shown in FIG. 9. The weight is additionally and primarily guided by a guide track or channel 64 (FIG. 9) which receives two cylindrical studs 66 projecting transversely from the weight at its forward and rear ends. These parts are also shown in FIG. 4-A, in which studs 66 are received between guide rails 64, the latter being molded integrally with one side of the gun. The same side of the gun also has bosses 68 which act as sockets to receive the ends of rod 52, the latter being bent at right angles to the main body of the rod. Rubber bushings 70 are preferably disposed between the ends of the rod and the bosses or sockets 68.

The cocking lever 16 is pivoted at 72 and has an offset extension 74 inside the gun. The parts 16 and 74 together constitute the cocking lever, and they may be turned downward from the position shown in FIG. 2 to that shown in FIG. 4, and then restored as shown in FIG. 5.

The lever has a link 76 extending rearward to a hook 78. The hook has transversely extending trunnions 80 which ride in guide tracks 82 molded integrally with one, and preferably both, sides of the gun, as will be seen also from inspection of FIGS. 7 and 9. The forward end of the recoil weight 30 preferably has a detent projection 84 at the top and another 86 at the bottom.

When the cocking lever 16 is turned down, as shown in FIG. 4, the link 76 and hook 78 move back to and engage the recoil weight 30. When the cocking lever is turned back or restored, as shown in FIG. 5, the weight 30 is pulled forward against the spring 32. There is a sear 88 for engaging and holding the weight 30 when the weight is in forward position, and at the same time the hook 78 is disengaged from the weight when the weight

is in forward position. This is accomplished by the shape of the hook guide track 82 previously referred to, for the forward portion 83 (FIG. 4-A) of the track is higher than the main body of the track and therefore the track acting on the trunnions 80 raises the hook 78 to disengage the detent 84 when the hook approaches its forward position, or more precisely when the weight has already been engaged by the sear 88. The sear 88 is normally urged upward by a spring 89 (FIG. 4) which is coiled about the pivot 90 of the sear.

Referring now to FIG. 5, the trigger 18 has means to release the sear 88 and thereby release the spring 89 to move the recoil weight abruptly rearward against the bumper 54. More specifically, the sear 88 is pivoted at 90 and has a forward extension 92. The trigger 18 has a rearward extension or lift 94. When the trigger is pulled the lift 94 raises the part 92, as shown in FIG. 6, thereby lowering the sear 88, and so releasing the weight 30.

In respect to the hook guides 82, and referring to FIG. 7, it will be noted that the top guide is raised at the rear end 96, while the bottom guide 98 retains the lower level of the main part of the guide track. This is to permit the hook 78 (FIG. 4) to rise over and engage the detent 84. The action may be gravitational, but preferably is made more certain by the provision of a leaf spring 100, the rear end of which bears downward on the top of the hook 78, while the forward end 102 is anchored in position by three molded pins 104, two of which are above the spring, while the third is below the spring, and so disposed as to flex the spring and thereby hold it in position.

The cocking lever 16, 74 also feeds the cap strip and cocks the hammer. When the cocking lever is turned down, as shown in FIG. 4, the arm 74 engages a hub formed on feed pawl 44 and located around the pin or trunnion 46. The latter is horizontally movable in a slot 106, and arm 74 forces the trunnion and pawl rearward from the position shown in FIG. 2 to that shown in FIGS. 4 and 5. Thus the pawl 44 moves the ratchet wheel 42 for one tooth, and this corresponds to a rotation of the anvil 36 (FIG. 10) corresponding to the spacing or pitch between pellets of gun powder on the cap strip. The pawl is urged into engagement with the ratchet wheel by a small pull spring 114 (FIGS. 2 and 5).

The cap strip is preferably of the perforated type, and in the present case is a double cap strip. A fragment of this cap strip is shown in FIG. 3-A, and it has two rows of perforations 108, as well as two rows of gun powder pellets 110. Reverting to FIG. 10, the anvil 36 has pins or sprocket teeth 112 which mate with the sprocket holes 108. When the cocking lever is restored, as shown in FIG. 5, the pawl 44 remains in rearward position. Thus the action of the cocking lever 16 serves to feed the cap strip.

Moreover, it cocks the hammer, and it will be recalled that the pin or trunnion 46 projects sidewardly from the hammer 40, as indicated in FIGS. 3 and 10. When the cocking lever is turned down, as shown in FIG. 4, the hammer is moved back by arm 74, and it is then engaged and held by the sear (FIG. 10) forming a part of the trigger. The trigger is normally turned forward, and therefore the sear 50 is moved upward, by a conventional trigger spring, which in the present case is coiled about the pivot 116 of the trigger. This spring is indicated at 118 in FIG. 2.

Referring to FIG. 3, the weighty die cast hammer 40 is slideable in horizontal guides which form a part of a die cast frame 120. The hammer has a rod 122 extending rearwardly therefrom, the said rod being slideable through a passage formed in stop ears 124 which form a part of the frame 120. The hammer spring 48 is a compression spring disposed around the rod 122. There are four guide rails for the hammer, one above the one below the hammer at each side of the frame 120,

and two of these guide rails are shown at 126 in FIG. 3.

Referring to FIG. 10, the cap roll 34 is slid over a stationary pin 130 projecting from one side of the frame previously referred to. The cap strip then passes around the anvil 36, it being held on the anvil by a shoe 132 carried at the forward end of an arm 134 pivoted at 136. Shoe 132 is grooved to pass pins 112. The arm is urged downward by a spring 138 coiled about the pin 136, as best shown in FIG. 3. The shoe 132 is preferably enlarged to act as a flash guard, as shown at 133 in FIG. 3. For the same purpose an upright wall or partition 140 (FIG. 10) is provided, this being cast with the frame. The used cap strip 142 is guided by a guide 144 also formed with the frame, and this guides the strip downward and forward out of the gun. To help clean the anvil of the cap strip, a wiper spring 146 is provided. The movable end of this spring or blade is notched at two places to clear the sprocket pins 112, and otherwise the blade scrapes the cylindrical surface 20 of the anvil. The thickness is exaggerated in FIG. 10.

To facilitate reloading a fresh roll of caps, the entire frame 120 may be turned down out of the gun, as shown in phantom lines in FIG. 7. This exposes the pin 130 over which the cap roll is slid, and it also 25 exposes the shoe 132 (FIG. 10) so that the latter may be lifted to receive the end of the cap strip therebeneath.

The cap firing mechanism is normally held up in working position by a releasable lock or latch, best shown in FIG. 8. This includes a release button 150 urged outward by a leaf spring 152, the spring being secured at 30 154. At its inner end button 150 carries a lock portion 156 of large diameter, and a release portion 158 of small diameter. The frame 120 of the cap firing mechanism has a pair of upstanding ears 160, and these have 35 the shape shown in FIGS. 2 and 7. When the button 150 is in the position shown in FIG. 8, the cap mechanism is held securely in raised position. However, when the button 150 is pressed inward, the large diameter portion 156 is moved out from between the ears, 40 and the small diameter portion 158 is moved between the ears. These are spaced more than the small diameter, and therefore the cap mechanism frame, together with the cocking lever, are all free to turn down as shown in FIG. 7. This action is not interfered with 45 by the link 76 and track 82, because the part 83 of the latter is extended forwardly.

We previously mentioned that the gun body is made in two halves which are molded out of plastics material, and which then are secured together in edge-to-edge relation. To help properly register the sides of the gun, and to strengthen their attachment, the meeting edges are provided with mating pins and holes which are molded as a part of the regular molding operation. The pins or dowells are shown around the periphery of the gun in FIGS. 2, 4, and 5, while the mating holes or sockets are shown around the periphery of the gun in FIG. 7. The mechanism is placed in the gun while it is still open, and therafter the sides are secured together, as by means of a suitable adhesive or cement or solvent. The mating of pins and sockets is shown in 50 FIG. 9 at 162 and 164. The gun body as molded includes sockets at 166 (FIGS. 2 and 7) for receiving a pin passing through the forward end of the cap mechanism frame, and on which the frame pivots when turned 55 down for reloading, as shown in FIG. 7. The sides also include sockets 168 (FIG. 7) for the pivot 90 (FIGS. 4 and 5) of the sear 88. Other significant parts are molded with the sides of the gun, as previously explained in connection with FIG. 4-A (the guides 64, the sockets 68, and the guides 82) and FIG. 7 (the guides 82).

It is believed that the construction, method of assembly, and the operation of our improved toy gun, as well as the advantages thereof, will be apparent from the foregoing detailed description. A child cocks and 75 fires the gun in the usual manner. When he fires the

gun he experiences a forcible recoil blow at the shoulder, exactly as though firing a real gun.

It will be apparent that, while we have shown and described our invention in a preferred form, changes may be made in the structure shown, without departing from the scope of the invention as sought to be defined in the following claims.

We claim:

1. A toy gun with recoil simulating mechanism, said gun comprising a guide means disposed longitudinally of the gun, a recoil spring extending longitudinally of said guide means, a recoil weight connected to said spring for movement along said guide means, a hook, a cocking lever having a link extending rearward to said hook, means whereby said hook moves back to and engages the recoil weight when the cocking lever is turned down and then pulls said weight forward against the recoil spring when the lever is restored, and a trigger for releasing the recoil spring to move the recoil weight abruptly rearward to simulate recoil.

2. A toy gun with recoil simulating mechanism, said gun comprising guide means disposed longitudinally of the gun, a recoil spring extending longitudinally of the gun, a recoil weight acted on by said spring and guided by said guide means for movement longitudinally of the gun, a hook, a cocking lever having a link extending rearward to said hook, means whereby said hook moves back to and engages the recoil weight when the cocking lever is turned down and then pulls the weight forward against the force of the recoil spring when the lever is restored, a sear for engaging and holding said weight when the weight is in forward position, means for disengaging the hook from the weight when the weight is in forward position, and a trigger for releasing the sear, thereby releasing the recoil spring to move the recoil weight abruptly rearward to simulate recoil.

3. A toy gun with recoil simulating mechanism, said gun comprising a guide rod disposed longitudinally of the gun, a recoil spring around said rod, a resilient bumper at the rear end of said rod, a recoil weight having a part disposed between said spring and said bumper, means to guide the weight for movement longitudinally of the rod, a hook, a cocking lever having a link extending rearward to said hook, means whereby said hook moves back to and engages the recoil weight when the cocking lever is turned down and then pulls said weight forward against the recoil spring when the lever is restored, a sear for engaging and holding said weight when the weight is in forward position, means for disengaging the hook from the weight when the weight is in forward position, and a trigger for releasing the sear and thereby releasing the recoil spring to move the recoil weight abruptly rearward against the bumper to simulate recoil.

4. A toy cap gun comprising cap strip feeding and firing mechanism including an anvil and a hammer, recoil simulating mechanism including a guide rod disposed longitudinally of the gun, a recoil spring around said rod, a resilient bumper at the rear end of said rod, a recoil weight connected to said spring, means to guide the weight for movement longitudinally of the rod, a cocking means for cocking said hammer and feeding the cap strip and for pulling said weight forward against the recoil spring, a sear for engaging and holding said weight when the weight is in forward position, and a trigger for releasing both the hammer and the sear and thereby releasing the recoil spring to move the recoil weight abruptly rearward against the bumper with simulated recoil as a cap is fired.

5. A toy cap gun comprising cap strip feeding and firing mechanism including an anvil and a hammer, recoil simulating mechanism including a guide means disposed longitudinally of the gun, a recoil spring disposed longitudinally of said guide means, a recoil weight connected to said spring and movable along said guide means, a hook, a cocking lever for cocking said hammer and feeding the cap strip, said lever having a link extending rear-

ward to said hook, means whereby said hook moves back to and engages the recoil weight when the cocking lever is turned down and then pulls said weight forward against the recoil spring when the lever is restored, and a trigger for releasing both the hammer and the sear and thereby releasing the recoil spring to move the recoil weight abruptly rearward with simulated recoil as a cap is fired.

6. A toy cap gun comprising cap strip feeding and firing mechanism including an anvil and a hammer, recoil simulating mechanism including a guide means disposed longitudinally of the gun, a recoil spring disposed longitudinally of said gun, a recoil weight connected to said spring for movement along the guide means, a hook, a cocking lever for cocking said hammer and feeding the cap strip, said lever having a link extending rearward to said hook, means whereby said hook moves back to and engages the recoil weight when the cocking lever is turned down and then pulls said weight forward against the recoil spring when the lever is restored, a sear for engaging and holding said weight when the weight is in forward position, means for disengaging the hook from the weight when the weight is in forward position, and a trigger for releasing both the hammer and the sear and thereby releasing the recoil spring to move the recoil weight abruptly rearward with simulated recoil as a cap is fired.

7. A toy cap gun comprising cap strip feeding and firing mechanism including an anvil and a hammer, recoil simulating mechanism including a guide rod disposed longitudinally of the gun, a recoil spring around said rod, a rubber bumper at the rear end of said rod, a recoil weight having a part disposed between said spring and said bumper, and means to guide the weight for movement longitudinally of the rod, a hook, a cocking lever for cocking said hammer and feeding the cap strip, said lever having a link extending rearward to said hook, means whereby said hook moves back to and engages the recoil weight when the cocking lever is turned down and then pulls said weight forward against the recoil spring when the lever is restored, a sear for engaging and holding said weight when the weight is in forward position, means for disengaging the hook from the weight when the weight is in forward position, and a trigger for releasing both the hammer and the sear and thereby releasing the recoil spring to move the recoil weight abruptly rearward against the bumper with simulated recoil as a cap is fired.

8. A toy cap rifle comprising a barrel, a breech portion, a hollow stock, a mechanism frame pivoted for movement out of the breech portion to receive a new roll of cap strip, cap strip feeding and firing mechanism including an anvil and a hammer in the mechanism frame, recoil simulating mechanism including a recoil spring in said stock, a recoil weight in said stock and acted on by said spring, means in said stock to guide the weight for movement longitudinally of the gun, a hook, a cocking lever pivoted on the mechanism frame for cocking said hammer and feeding the cap strip, said lever having a link extending rearward to said hook, means whereby said hook moves back to and engages the recoil weight when the cocking lever is turned down and then pulls said weight forward against the recoil spring when the lever is restored, a sear for engaging and holding said weight when the weight is in forward position, means for disengaging the hook from the weight when the weight is in forward position, and a trigger for releasing both the hammer and the sear and thereby releasing the recoil spring to move the recoil weight abruptly rearward with simulated recoil as a cap is fired, said link being so disposed relative to the mechanism frame and the hook that the link does not interfere with movement of the mechanism frame out of the breech portion of the gun to receive a new roll of cap strip.

9. A toy cap rifle comprising a barrel, a breech portion, a hollow stock, a mechanism frame pivoted for movement out of the breech portion to receive a new roll of cap strip, cap strip feeding and firing mechanism in-

cluding an anvil and a hammer in the mechanism frame, recoil simulating mechanism including a guide rod disposed longitudinally of the gun inside the hollow stock, a recoil spring, a recoil weight acted on by said spring, means to guide the weight for movement longitudinally of the rod, a hook, a cocking lever pivoted on the mechanism frame for cocking said hammer and feeding the cap strip, said lever having a link extending rearward to said hook, means whereby said hook moves back to and engages the recoil weight when the cocking lever is turned down and then pulls said weight forward against the recoil spring when the lever is restored, a sear for engaging and holding said weight when the weight is in forward position, means for disengaging the hook from the weight when the weight is in forward position, and a trigger for releasing both the hammer and the sear and thereby releasing the recoil spring to move the recoil weight abruptly rearward with simulated recoil as a cap is fired, said link being so disposed relative to the mechanism frame and the hook that the link does not interfere with movement of the mechanism frame out of the breech portion of the gun to receive a new roll of cap strip.

10. A toy cap rifle comprising a barrel, a breech portion, a hollow stock, a mechanism frame pivoted for movement out of the breech portion to receive a new roll of cap strip, cap strip feeding and firing mechanism including an anvil and a hammer in the mechanism frame, recoil simulating mechanism including a guide rod disposed longitudinally of the gun inside the hollow stock, a recoil spring around said rod, a rubber bumper at the

5 rear end of said rod, a recoil weight having a part disposed between said spring and said bumper, means to guide the weight for movement longitudinally of the rod, a hook, a cocking lever pivoted on the mechanism frame for cocking said hammer and feeding the cap strip, said lever having a link extending rearward to said hook, means whereby said hook moves back to and engages the recoil weight when the cocking lever is turned down and then pulls said weight forward against the recoil spring 10 when the lever is restored, a sear for engaging and holding said weight when the weight is in forward position, means for disengaging the hook from the weight when the weight is in forward position, and a trigger for releasing both the hammer and the sear and thereby releasing 15 the recoil spring to move the recoil weight abruptly rearward against the bumper with simulated recoil as a cap is fired, said link being so disposed relative to the mechanism frame and the hook that the link does not interfere with movement of the mechanism frame out of the breech 20 portion of the gun to receive a new roll of cap strip.
